197,513

CHAIR

Hubert H. Crawford, 231 Humboldt Parkway,
Buffalo, N.Y.

Filed July 8, 1963, Ser. No. 75,692

Term of patent 14 years

(Cl. D15—1)

The appearance of the chair of my design is substantially the same as viewed in side elevation from either side thereof.

I claim:

The ornamental design for a chair, as shown and described.
